Inventor

Samuel Sedranksy

By his Attorney

L. S. Sedranksy

UNITED STATES PATENT OFFICE.

SAMUEL SEDRANSKY, OF BRONX, NEW YORK, ASSIGNOR TO SAMUEL MARCUS, OF BROOKLYN, NEW YORK.

WRISTBAND ADAPTED FOR CARRYING ARTICLES.

Application filed May 27, 1921. Serial No. 473,117.

To all whom it may concern:

Be it known that I, SAMUEL SEDRANSKY, a citizen of the United States, residing at Bronx, in the county and State of New York, have invented certain new and useful Improvements in Wristbands Adapted for Carrying Articles, of which the following is a specification.

This invention relates to a wrist band 10 adapted for carrying articles, particularly coins or other valuables, and an object of the invention is to provide a simple and efficient device for this purpose which will be both of an attractive appearance and capable of being manufactured at small cost.

Other objects and aims of the invention, more or less specific than those referred to above, will be in part obvious and in part pointed out in the course of the following 20 description of the elements, combinations, arrangements of parts and applications of principles, constituting the invention, and the scope of protection contemplated will be indicated in the appended claim.

25 In the accompanying drawings which are to be taken as a part of the specification, and in which I have shown merely a preferred form of embodiment of the invention:—

30 Figure 1 is a side elevational view of a band constructed in accordance with this invention, the receptacle carrier being shown in transverse section, and

35 Figure 2 is a top plan view, partly broken away, of the device seen in Fig. 1.

Referring to the drawings for describing in detail the structure which is therein illustrated, the reference character L indicates the wrist band proper. This may consist of 40 a leather, cloth, or other suitable strap having a buckle device 1 for connecting together its opposite ends in position encircling a wearer's wrist.

The reference character G indicates the 45 article carrier. This may be constructed in any suitable or approved manner capable of containing the articles and efficiently guarding them against possible loss. In the exemplary structure illustrated, however, the 50 article carrier consists of a lower, or base, member 2 and an upper, or cover, member 3. These parts may be made of any desired shape, or may be ornamented in any suitable manner. As illustrated, they are shaped to 55 form a simple flat cylindrical box; that is,

a box having the general form of a so-called "pill-box".

Both of these members are preferably stamped from sheet metal tho obviously they may be formed of any other appropriate 60 material.

The base member has its flat bottom wall 4 provided with a pair of apertures, or slots, 5 and 6, therethru thru which the strap, or band, member L is threaded, being introduced thru the slot 5 into the interior of the box and thence passing outwardly again thru slot 6.

The cover member is provided with a pair of oppositely disposed ears 7 and 8 thereon 70 and these ears are formed with openings 9 and 10 respectively.

The strap L is threaded thru the opening 9, said strap and the walls of said opening constituting a pivot bearing by which the 75 cover member is suitably pivotally connected in position to be swung on to, or off of, the base member.

A fastening tab H is connected with ear 8 and carries a snap fastener element 11 80 adapted to engage with a cooperative element 12 carried by the strap L for holding the cover member in closed position when desired.

The fastening tab may be made in any 85 appropriate manner but preferably consists of a short length of strap material folded upon itself and extended thru the opening 10, the free ends of the strap material being permanently held together 90 by the snap fastener element 11.

In use the wearer, having adjusted the strap L about his wrist, can readily open the box G by disengaging the snap fastener and swinging the cover member upwardly. 95 After the desired articles have been placed within the base member the cover is returned to closed position and the snap fastener engaged together.

Sliding the base member along strap L, 100 toward or away from the snap fastener element 12, a proper degree of tension may be placed upon the fastening tab for correctly holding the cover closed, and in this connection it is to be particularly noted 105 that the hinge connection provided between the strap and the ear 7 is such that tightening of the buckle 1 will serve to hold the cover member more tightly in position, and that the resultant strain upon the snap 110

fastener will be one exerting practically no tendency to release said fastener.

As many changes could be made in this construction without departing from the scope of the invention as defined in the following claim, it is intended that all matter contained in the above description, or shown in the accompanying drawings, shall be interpreted as illustrative only and not in a limiting sense.

Having thus described my invention, what I claim as new and desire to secure by Letters Patent is:—

A device of the character described comprising a box body having a bottom and sides and which bottom is slotted at opposite points, a removable cover for said body and having a rim fitting downwardly over and encompassing the sides thereof, said rim at the opposite sides of its lower edge having integrally therewith outwardly and

downwardly extending slotted ears, a strap to extend around the wrist and having a buckle for tightening the same upon the wrist, said strap being threaded from one end inwardly through one of said slotted ears and then upwardly through the adjacent slot in the bottom of said body and then downwardly through the other slot in said bottom and thence extending to said buckle, and a strap fastening tab connected with the other slotted ear of said cover and thence extending outwardly over said wrist strap and at its outer end being detachably secured thereto for securing said cover in closed position.

In testimony whereof I affix my signature in the presence of two witnesses.

SAMUEL SEDRANSKY.
